CHARLES L. REESE, OF WILMINGTON, DELAWARE, ASSIGNOR TO E. I. DU PONT DE NEMOURS AND COMPANY, OF WILMINGTON, DELAWARE, A CORPORATION OF DELAWARE.

BURSTING CHARGE FOR CONTAINERS INTENDED TO BE EXPLODED, AND PROCESS OF FORMING SAID CHARGE.

1,309,588.

Specification of Letters Patent.

Patented July 8, 1919.

Application filed August 4, 1917. Serial No. 184,490.

To all whom it may concern:

Be it known that I, CHARLES L. REESE, of Wilmington, in the county of New Castle, and in the State of Delaware, have invented 5 a certain new and useful Improvement in Bursting Charges for Containers Intended to be Exploded, and Processes of Forming Said Charges, and do hereby declare that the following is a full, clear, and exact description 10 thereof.

This invention relates to bursting charges for containers intended to be exploded, such as shells, grenades, torpedoes, mines, etc., and processes of forming said charges in the 15 containers which are to hold them.

The object of the invention is to provide such a bursting charge and process which shall have, among others, the advantages of rendering available new sources of raw materials; of providing materials capable of being used for the purpose, either by themselves or with others; and of providing a process by which said mixtures can be cast into shells or other containers intended 20 to be exploded, and there caused to solidify and completely fill the space provided for the charge, and to such ends the invention comprises the bursting charge for shells, grenades, torpedoes, mines and other containers intended to be exploded, and the 25 process of forming the same hereinafter specified.

In the accompanying drawing—

The figure is an axial section of a shell 30 containing a bursting charge embodying my invention.

The invention is capable of being carried out in many different ways, but for the purpose of illustration only one form of the 35 invention will be described herein.

In filling with bursting charges, containers intended to be exploded, such as shells, grenades, torpedoes, mines, etc., it is desirable to introduce the largest possible charge 40 into a given space, so as to produce the maximum possible bursting effect. Trinitrotoluol has heretofore been used to a very large extent, because, among other reasons, it has a relatively low melting point and is therefore 45 easily melted; it can be kept melted while being introduced into the shell or other body,

and it does not freeze or solidify until it has reached the final condition in which it is to remain. The supply of trinitrotoluol, however, may not be adequate, and it is very desirable to render other materials available to replace the trinitrotoluol wholly or in part. I have discovered a new bursting charge for the said purpose, which is of high power, and which may consist wholly of a new substance, or of such substance combined with other explosives. While the said substance is useful and valuable when introduced into the shell or other container in solid condition, its melting point is too high to permit it, as 55 a practical matter, to be melted and cast into the shell. I have therefore invented a process by which the said substance can, in effect, become part of a molten mass, of such low melting point as to be capable of being successfully cast into the shell. 60

The new substance to which I refer is produced by the nitration of aromatic hydrocarbons of the benzene series, having a higher boiling point than toluene, for instance a 75 boiling point between 130-142° C. and, in particular, by the nitration of xylene. The nitration is accomplished by the use of strong nitric and sulfuric acid, and the action is preferably so controlled as to produce 80 a solid, finely divided product. I find that when starting with xylene I am able to prepare a solid nitroxylene, which approximates trinitroxylene in composition.

This product can be detonated by ordinary 85 commercial detonators, and has an explosive force nearly equal to that of trinitrotoluol.

In charging a shell, the nitroxylene may be pressed into the shell in a dry condition, making a compact charge which is readily 90 detonated by the usual primer, or it may be mixed with another nitro compound, such, for example, as trinitrotoluol.

In order to get the effect of completely casting the shell or other container full of 95 the explosive, I mix the said aromatic nitro bodies, made from the aromatic hydrocarbons, having boiling points higher than toluol, with more easily fusible nitro bodies, such as trinitrotoluol, and cast the mixture 100 together into the shell. For example, a mixture of approximately 40% nitroxylene and

60% trinitrotoluol can be thus cast. Desirable proportions are 50 to 70 parts of trinitrotoluol and 50 to 30 parts of nitroxylene.

In the figure of the accompanying drawing, I have shown, more or less diagrammatically, a shell body 1, having within it a bursting charge 2, such as I have described, and having a fuse 3 containing a detonator for detonating the bursting charge 2.

By thus mixing and casting the charges, it is not necessary to use temperatures greatly above those of the more easily fusible nitro bodies, and yet substantially the same effect is obtained as if the more difficultly fusible nitro bodies were melted and cast into the shell or other container, if that were feasible.

The trinitrotoluol used may be either a crude product, such as obtained by direct nitration of toluol, or a product obtained by refining the crude product. The mixture is prepared for casting by melting the trinitrotoluol and to this melted product adding the solid trinitroxylool, keeping the temperature of the mixture well above the melting point of the trinitrotoluol. Thorough mixing of the two explosives can be carried out by any suitable method of mechanical agitation, or simply by stirring with a paddle by hand. Only a very small proportion of the trinitroxylool is soluble in or melted by the trinitrotoluol.

It is not necessary that the mixture produce a homogeneous liquid product, but the trinitroxylool can be added in very appreciable amounts until the mixture carries a maximum percentage of trinitroxylool in suspension. The maximum percentage that can be added in suspension is determined by whether the mixture can be poured. Such a mixture is, as stated, represented by one carrying 60% of trinitrotoluol and 40% of trinitroxylool, such a mixture pouring nicely at about 80° C. Higher percentages of trinitroxylool can be used, especially if higher temperatures are employed and lower percentages of trinitroxylool of course can be used satisfactorily. I prefer, however, the 60-40 mixture, inasmuch as it produces a mixture that can be easily poured and gives a casting of excellent physical and explosive properties.

This invention thus makes it possible to fill a shell as completely with a charge consisting partly of the more difficultly fusible nitro bodies as it has heretofore been pos-

sible to fill them with the more easily fusible nitro bodies, and in particular furnishes substitutes for trinitrotoluol by which bursting charges can be produced that are substantially as effective as if they consisted entirely of trinitrotoluol.

By the term "container", as used in the claims, is meant a container intended to be exploded, such as a shell, grenade, torpedo, mine, etc.

I claim:

1. A bursting charge comprising the combination of trinitroxylene with another organic nitro-compound having a lower melting point.

2. A bursting charge comprising the combination of a highly nitrated xylene with trinitrotoluol.

3. A bursting charge comprising the combination of a nitrated xylene which is solid at ordinary temperatures, with trinitrotoluol, in such proportions that the mixture can be poured at temperatures below 100° C.

4. A bursting charge comprising the combination of 50 to 70 parts of trinitrotoluol and 50 to 30 parts of a nitrated xylene.

5. A bursting charge comprising a liquid containing molten trinitrotoluol having a nitrated xylene dissolved therein.

6. A bursting charge comprising a liquid containing molten trinitrotoluene having a nitrated xylene in suspension therein.

7. A bursting charge comprising a liquid containing molten trinitrotoluene having a nitrated xylene dissolved and in suspension therein.

8. A bursting charge comprising a liquid containing molten trinitrotoluene having a nitrated xylene therein in excess of the amount soluble in the trinitrotoluene.

9. A bursting charge comprising a liquid containing molten trinitrotoluene having trinitroxylene dissolved therein.

10. A bursting charge comprising a liquid containing molten trinitrotoluol having trinitroxylene suspended therein.

11. A bursting charge comprising a liquid containing molten trinitrotoluol having trinitroxylene dissolved and suspended therein.

12. A bursting charge comprising a liquid containing molten trinitrotoluol having trinitroxylene therein in excess of the amount soluble in the trinitrotoluene.

In testimony that I claim the foregoing I have hereunto set my hand.

CHARLES L. REESE.
